UNITED STATES PATENT OFFICE.

ALBERT E. NEWTON AND FRED K. HENDRICKSON, OF WORCESTER, MASSACHUSETTS,
ASSIGNORS TO REED-PRENTICE COMPANY, A CORPORATION OF MASSACHUSETTS.

DROP-TABLE MECHANISM FOR MILLING-MACHINES.

1,169,180.

Specification of Letters Patent. Patented Jan. 25, 1916.

Application filed December 21, 1914. Serial No. 878,270.

To all whom it may concern:

Be it known that we, ALBERT E. NEWTON and FRED K. HENDRICKSON, citizens of the United States, both residing at Worcester, 5 in the county of Worcester and State of Massachusetts, have invented a new and useful Drop-Table Mechanism for Milling-Machines, of which the following is a specification.

10 This invention relates to a milling machine and the principal objects thereof are to provide arrangement for positively dropping the table after the cutting operation is finished, in such form that it is simplified 15 and rendered less expensive to make and keep in condition than has been the case with table drop devices with which we are familiar; to provide a simple and practicable means for holding the table rigidly 20 while it is in its raised position so as to prevent chattering; to provide, in combination with the table dropping means, a simple and convenient arrangement by which the table will be caused to drop while on the 25 high speed and will be reversed and fed back without changing the speed, and to provide driving shaft dropping means for stopping it on the high speed before it comes into cutting position so that when 30 started again it will start on the high speed and then will be reduced during the cutting operation only.

The invention also involves improvements in details of construction and combinations of parts as will appear.

Reference is to be had to the accompanying drawings in which—Figure 1 is a front elevation of a milling machine of the Lincoln type showing a preferred embodiment 40 of this invention applied thereto; Fig. 2 is an end elevation of the same; Fig. 3 is a view similar to Fig. 2 on enlarged scale showing a part only of the mechanism; Fig. 4 is a plan of the work table and connected 45 parts; Fig. 5 is a sectional view of the line 3—3 of Fig. 3; Fig. 6 is a side elevation of the change speed gearing; Fig. 7 is a plan thereof showing the reverse gearing; Fig. 8 is an end view showing a modification; Fig. 9 is a rear elevation of the same; and 50 Fig. 10 is an end view of the cam thereof showing the surface on which it rests in section.

The invention is shown as applied to a

milling machine having a bed or frame 10 55 on which are supported a head stock 11 and tail rest 12, the latter not appearing in Figs. 2 and 3. Carried with the head stock are bearings 13 for a cone pulley 14 to which power is transmitted from a countershaft. 60 Ordinary mechanism 15 is shown for raising and lowering the head center.

On the bed are located ways 16 on which is adjustably mounted as usual a carriage 17, movably longitudinally with respect to the driving spindle by a screw and hand wheel 9. Pivoted on a stud 18 on this carriage is a drop table or work table support 19 having ways 20 for the sliding work table 21.

On the shaft on which the cone pulley 14 is located is a small gear or pinion 22 meshing with a gear 23 on the driving spindle 24 which is provided with means for centering and driving the cutter spindle 25. A 75 cutter 26 is shown on this spindle. The other end of this spindle is supported as usual by a tail center carried by the tail rest 12. Also shown on the shaft of the cone pulley are a pair of pulleys 28 for 80 driving pulleys 29 on a shaft 30. This shaft 30 is mounted in a gear feed change box 31 for driving (by any ordinary gearing) a shaft 32 which is connected by a knuckle joint 33 with a table driving shaft 34, which is provided with a worm 35 and a handle 36. This shaft 34 accordingly is capable of swinging on the knuckle joint as a center. The gear box 37 in which it is located is provided with a slot 38 for limiting its downward motion.

The worm 35 meshes with a worm wheel 39 loosely mounted on a shaft 40 in this gear box 37. Also mounted on the shaft 40 is a bevel gear 41 meshing with a bevel gear 42 on a shaft 43 parallel with the shaft 40. This shaft 43 is provided with a spur gear 44 meshing with a spur gear 45 loose on the shaft 40. By means of a clutch 46 either the spur gear 45 or worm wheel 39 95 can be fixed to the shaft 40 in an ordinary manner so as to drive this shaft either at the speed of the shaft 43 or at a much lower speed through the worm gear.

The shaft 40 is provided with a spur gear 48 on the rear end which meshes with an idle gear 49 of the same size which in turn meshes with a gear 50 of the same size loose

on a shaft 51. On this shaft 51 is loosely located another gear 52 meshing with a gear 53 tight on the shaft 40. A clutch 54 secures either the gear 50 or 52 to the shaft 51 and thus provides for driving in either direction. The shaft 51 by means of gears 55 drives a feed screw 56 meshing with a nut (not shown) on the work table 21 for operating the same.

10 The clutches 46 and 54 can be operated by hand by applying a wrench to the square ends of a shaft 57 or sleeve 57^a. The clutch 46 is connected with a lever 58 which is connected by a link 59 with an arm 60 adapted to turn on a stud 61. For the purpose of turning this arm in opposite directions from its normal position shown in Fig. 3 two arms 62 and 63 are also pivoted on the stud and provided with means for turning the arm 60 when depressed.

15 A pair of plungers 64 and 65 are provided resting on these arms. The depression of the plunger 64 moves the arm 62 down and the arm 60 to the right in Fig. 3 and moves the clutch to the left at Fig. 6 so as to connect the shaft 56 with the high speed. The depression of the other plunger 65 operates through the arm 63 to give the opposite effect and connect this shaft with the slow speed through the worm gear 39. It is to be noted that the work table is provided as usual with swinging dogs 66 for operating the two plungers 64 and 65 and with similarly shaped but differently arranged reversing dogs 67 for engaging and operating the reversing plungers 68. The latter control the reverse through a lever 69 and connections.

20 One of the main features of this invention relates to the drop of the table 19. This drop table is capable of a swinging motion at the end sufficient to drop the work down after the cut is made and allow it to feed back with the work out of contact with the cutter. This is accomplished by a lever 72 pivoted on a stud 73 on the carriage 17. This lever is provided with a stud 74 which is pivoted to a link 75 which in turn is pivoted to the end of the drop table 19. 25 This provides a toggle joint for operating the drop table positively in both directions and raising it exactly to a predetermined elevation.

25 When the lever 72 is in vertical position as shown in Fig. 2 the table is raised to its highest position but when the lever is moved out to the right it causes the link 75 to swing outwardly and allows the table to drop slightly. For the purpose of operating this lever the work table 21 is provided with two arms 78 and on these are mounted adjustable stops 79 and 80 for engaging the end of this lever 72 at opposite ends of the travel of the table. In the position shown in Fig. 3 the stop 80 has just engaged the

lever 72 and moved to its upright position, thus forcing the table up ready for the cutting stroke.

It is to be noted that the drop table is provided with a stud 81 on which is hung a screw 82 having a nut on the bottom. The carriage 17 is provided with a perforated ear 83 through which this screw passes. This nut is adjusted up to the proper position to cause it to bind when the table is raised to its highest position, thus securely holding it against chattering during the working stroke.

30 The table is provided with a pivoted dog 86 adapted to engage the end 87 of a lever 89 88 on the rear side of the machine. This lever is connected by a link 85 with a drop work lever 89 having a projection 90 on the bottom for engaging an arm 91 supporting the table driving shaft. However, when the dog 86 operates this arm 87 to push it out the lever 89 will be operated to release the shaft 34 and allow it to drop away to its lowermost position where the gears 44 will be out of mesh. The lever 89 can be operated by hand through a handle 93.

35 The operation of the machine is as follows:—Assuming that the driving shaft 34 is down in inoperative position, it will be understood that the shaft 34 is being driven by power and that the cutter 26 is rotating. The work table is back away from the cutter but not in its extreme rear position. In order to start the operation the only thing necessary is to grasp the handle 36 and raise the worm until it meshes with the worm wheel and the gears 44 and 45 also mesh. Then the projection 90 is automatically moved into position by a spring 92 to hold up the shaft until released. The table thus starts forward at full speed being driven by the gears 44 and 45. When the table moves substantially into position for the work to engage the cutter one of the dogs 66 engages the top of the plunger 65 and forces it down. This moves the clutch 46 over to release the gear 45 and engage the worm wheel 39. This reduces the speed of the feed until the cutting operation is completed. At that time the other dog 66 engages the plunger 64 and moves the clutch back to its former position so as to cause the table to continue its motion in the same direction at high speed. Shortly after this change the table moves into such position that the stop 79 engages the lever 72 and slightly afterward one of the reversing dogs 67 on the other side of the table engages its reversing plunger 68. In this way the table is dropped and then immediately the feed is reversed but the reverse of course is carried on at the high speed. The table then moves back to the end of the stroke at high speed out of the way of the cutter when the stop 80, moves the lever 72 against a stop

94 and the other dog 67 engages the reverse plunger 68. Thus the table is raised to its working position and then reversed but still moves at the high speed. On starting back the 5 dog 86 engages the end 87 of the lever 88 and drops the worm shaft down out of operative position. This stops the feed, leaving the parts in the position in which they were assumed to have started. It will be seen therefore that the table is dropped and raised 10 in a positive and thoroughly mechanical manner and that when raised it is held there by an exceedingly simple device. Furthermore the toggle joint for raising and lowering the table is capable of being formed in 15 a strong and durable manner without excessive expense and will not require frequent repairs or adjustment. By connecting the shafts 40 and 51 by two trains of gears 20 one containing an odd number and the other an even number, it will be seen that the driven shaft can be rotated in either direction.

In the form shown in Figs. 8 and 9, the 25 table is dropped with a different motion in such a way as to take less time and necessitate a shorter travel of the sliding table and of the operating lever in order to cause the table to drop. In this way the operating 30 lever can be engaged by the actuating stop on the sliding table before the cutting operation is completed and dropped suddenly when the cutting operation is finished and immediately reversed if desired. In this 35 case the lever 95 corresponding with the lever 72 is pivoted on the carriage and its end is adapted to be operated by the stops 79 and 80 in the same way as above described. This lever, however, is provided with two 40 members, a projection 96 and a spring-controlled pawl 97, for operating studs 98 projecting from the face of a rotary cam member 99. This cam member is mounted on a shaft 100 which has a similar cam member 45 and set of duplicate parts on the other end. The cam member is provided with a number of projecting surfaces 101 equal in number to the number of studs 98, and these are designed to rest on a raised surface 50 102 on the carriage which has an abrupt drop at one end, and an incline at the other. The surfaces 101 are all concentric with the shaft 100 but they drop off slightly to form non-concentric cam surfaces 103, each of 55 which is connected with the next concentric surface 101 by a preferably radial surface 104. The operation is as follows:—Upon 60 the swinging of the lever 95 to the right by means of the stop 79, the projection 96 engages one of the studs 98 and turns the shaft 100 far enough to turn the surface 104 past the abrupt end of the surface 102 so as to allow the shaft, and consequently 65 the drop table which carries the shaft, to drop. Upon the other stroke when the stop

80 engages and operates the lever 95 in the opposite direction the pawl is caused to engage another one of the studs 98 and to positively turn the shaft 100 in the same direction an equal distance. This results 70 in lifting the next surface 103 upon the surface 102 until the concentric surface 101 rests thereon. In this way the table is raised and held at a definite height. In this form the screw 82 is shown as provided with a 75 stiff spring 106 located in a cylinder 107. Its purpose is to hold the table the same way as in the other form shown but not with absolute rigidity.

Although we have illustrated and described, our invention as applied only to the Lincoln type of milling machine and have shown only a single modification of the invention, we are aware of the fact that many modifications can be made therein without departing from the scope of the invention as expressed in the claims, and that it can be applied to other types of milling machines. Therefore, we do not wish to be limited to this particular type of machine, 85 or to all the details of construction herein shown and described, but

What we do claim is—

1. In a milling machine, the combination 95 with a drop work table, of positive means for automatically raising it, holding it at a constant level throughout the working stroke, and then allowing it to descend and means carried by the table for actuating said positive means.

2. In a milling machine, the combination 100 with a work table support pivoted at one end, and a sliding work table supported thereon, of means for raising the free end of said work table, and means operated by the sliding work table for causing said work table to drop when it moves to a predetermined point.

3. In a milling machine, the combination 105 with a drop work table mounted to move up and down, and a sliding work-table supported thereon, of a toggle joint connected with said work table for raising it and means connected with the sliding table for operating said toggle joint.

4. In a milling machine, the combination 110 with a drop work table pivoted near one end, of a toggle joint connected with the other end for raising it, and reciprocating means supported on said table for operating 115 said toggle joint.

5. In a milling machine, the combination 120 with a pivoted work table support, of a link connected with the free end thereof, a lever pivoted to a stationary part of the machine 125 and also connected to said link, whereby when said lever is operated the end of the table support will be raised or lowered, means for operating the lever, and means connected with said table support for hold- 130

ing it firmly in position when elevated so as to prevent chattering.

6. In a milling machine, the combination with a pivoted work table support, of a lever connected with the free end thereof, means whereby when said lever is turned the end of the table support will be raised or lowered, and means connected with said table support for holding it firmly in position when elevated so as to prevent chattering, said means comprising a screw connected with the table support and having a nut on the end and adapted to engage the bottom of a stationary part of the machine when the table is elevated.

7. In a milling machine, the combination with a work table, a cutter spindle and means for reciprocating the table, of means whereby the table will be raised or lowered, and means connected with said table for limiting its upward motion and holding it firmly in position when elevated so as to prevent chattering.

8. In a milling machine, the combination with a pivoted work table support, a work table slidably mounted thereon, a toggle lever connected with said support for raising and dropping it and two adjustable stops on said sliding table for engaging and operating said toggle lever.

9. In a milling machine, the combination with a sliding table, of means for driving the sliding table comprising two shafts, two trains of gears for connecting said shafts, all the gears of each train being constantly in mesh and means for connecting either train of gears with the shafts, one train containing an even number and the other an odd number of gears.

40. 10. In a milling machine, the combination

with a drop table and a sliding table thereon, of means for driving the sliding table comprising a bodily movable shaft, a hooked lever for holding said shaft in operative position, dogs on the sliding table, and connections operated by said dogs for pulling said lever back to release and drop the shaft.

11. In a milling machine, the combination with a sliding table, of means for driving the sliding table comprising two shafts, two trains of gears for connecting said shafts, and means for connecting either train of gears with the shafts, one train containing an even number and the other an odd number of gears, a movably mounted driving shaft, a hooked lever for holding the driving shaft in operative position, and means for pulling said lever back to release and drop the driving shaft.

12. In a milling machine, the combination with a sliding table, of means for driving the sliding table comprising a shaft having a worm thereon, a gear driven by said shaft, a second shaft, a worm gear meshing with said worm, a gear meshing with the first gear, both said gear and worm gear being loose on the second shaft, and means operated by the table for connecting either the gear or worm gear with the second shaft for driving it from the first shaft at high or low speed.

In testimony whereof we have hereunto set our hands, in the presence of two subscribing witnesses.
